ENVELOPE

Harlan M. Whitman, West Hartford, Conn., assignor to Curtis 1000, Incorporated, Hartford, Conn., a corporation of Minnesota

Application October 2, 1947, Serial No. 777,401

2 Claims. (Cl. 229—92.1)

1

This invention relates to correspondence envelopes of paper and particularly to envelopes adapted for business notices and communications which may qualify as third class mail.

An object of the invention is to provide an envelope adapted for single mailing and on which a message may be written before final folding of the envelope into position for mailing.

Another object of the invention is to provide an envelope on the inner surface of which a message may be printed or written which will permit inspection by the postal authorities while the message is normally maintained out of view by the folds of the envelope.

With the above and other objects in view the invention may include the features of construction and operation set forth in the following specification and illustrated in the accompanying drawing.

In the accompanying drawing annexed hereto and forming a part of this specification I have shown the invention embodied in two forms of correspondence envelopes but it will be understood that the invention can be otherwise embodied and that the drawing is not to be construed as defining or limiting the scope of the invention, the claims appended to this specification being relied upon for that purpose.

In the drawing:

Fig. 1 is an outline of the sheet forming an envelope made according to the present invention prior to its being folded;

Fig. 2 is an outline of the envelope shown in Fig. 1 partially folded and as used by the sender;

Fig. 3 is a completely folded view of the envelope shown in Figs. 1 and 2 ready for mailing;

Fig. 4 is an outline before folding of another form of envelope made according to the present invention;

Fig. 5 is a partially folded view of the envelope shown in Fig. 4 ready for receiving the printed or written message and Fig. 6 is a completely folded view of the envelope ready for mailing.

In the above mentioned drawing, there have been shown but two embodiments of the invention which are now thought to be preferred, but it is to be understood that changes and modifications may be made within the scope of the appended claims without departing from the spirit of this invention.

Referring more in detail to the figures of the drawing and first to the form of the invention shown in Figures 1, 2 and 3, it will be seen that this envelope includes a central panel 10, two gummed flaps 12 and 14, and two large un-

2

gummed panels 16 and 18. The gummed flaps 12 and 14 may extend along one side and one end respectively of the central panel 10. The longer flap 12 has its free edge gummed and the shorter flap 14 is wider and has a portion only of its width gummed throughout its length. The free edge of flap 14 is left ungummed for a purpose presently to be described. Flap 14 is moistened and its gummed portion is made to adhere to the surface of the central panel 10 preferably before printing or writing the message or information on the inner surfaces of the panels 10, 16 and 18.

To prepare the envelope for mailing the panel 16 has its end edge tucked under the free end ungummed margin of the flap 14. The panel 18 is then folded over the panel 16 and flap 14 and finally the flap 12 is folded over the free end of panel 18. With the flap 12 moistened and adhering to the outer surface of panel 18 the printed matter or message will be concealed but may be inspected by carefully withdrawing panel 16. With the panel 16 withdrawn, or by turning back the ungummed margin of flap 14, the inner surfaces of panels 10, 16 and 18 will be visible when the envelope is bowed outwardly by compressing the upper and lower edges.

The envelope may be opened in the same manner as a conventional envelope by slitting along the fold between panel 10 and flap 12. The panels 16 and 18 may then be readily unfolded to present the entire printed matter in convenient and readable form. If desired, perforations 20 may be provided adjacent or along the fold between panels 10 and 16. This panel may then be readily detached for remailing.

Referring to the form of the invention shown in Figs. 4, 5 and 6, it will be seen that the envelope comprises a central panel 24, and a panel 26 extending from one of the longer sides. In addition two oppositely disposed flaps 28 are provided extending from the shorter sides of panel 24. A third flap 30 of conventional triangular form with its free edge gummed is also provided. The two flaps 28 are gummed over their entire area and are folded down directly upon the inner surface of panel 24 and adhered thereto. In this folded and attached position they reinforce the opposite edges of the panel 24 and eliminate raw edges.

With the flaps 28 in the position shown in Fig. 5, the envelope may be printed or a message written thereon. The envelope may then be prepared for mailing by folding the panel 26 over panel 24 and gumming and folding the flap 30 over the free end or outer surface of panel 26.

The printed or written matter on the inner surfaces of panels 24 and 26 may be inspected by bowing the panels 24 and 26 outwardly by compressing their upper and lower edges. The envelope also may be opened in the usual manner by slitting along the edge or fold between panel 24 and flap 30.

I claim:

1. An envelope comprising a central panel, a side panel extending from one edge thereof, a flap extending from said central panel at the opposite edge from said side panel, said flap being partially gummed and having a free edge under which said side panel may be tucked when folded, a second panel extending from another side edge of said central panel, and a gummed flap from another edge of said central panel to which said second panel may be attached.
2. An envelope comprising a central panel, two side panels extending from adjacent edges of said central panel, and two gummed flaps extending from the remaining sides of said central panel, one of said flaps being adhesively attached to said central panel and having a free ungummed

5

edge under which the free end of one of said side panels may be tucked, the other side panel being adhesively attached to said second flap.
